[57] CLAIM

The ornamental design for a personal computer stand, as shown and described.

DESCRIPTION

FIG. 1 is a top, front, right side perspective view of the personal computer stand showing our new design;

FIG. 2 is a left side elevational view thereof;

FIG. 3 is a right side elevational view thereof;

FIG. 4 is a front elevational view thereof;

FIG. 5 is a top plan view thereof;

FIG. 6 is a bottom plan view thereof;

FIG. 7 is a rear elevational view thereof.

The stand is shown in the level position in FIGS. 1, 2, 3, 4, 5 and 7.
